UNITED STATES PATENT OFFICE.

MORTIMER H. MOORE, OF CHICAGO, ILLINOIS.

SAFE.

Application filed July 25, 1923. Serial No. 653,679.

To all whom it may concern:

Be it known that I, MORTIMER H. MOORE, a citizen of the United States of America, and resident of the city of Chicago, in the 5 county of Cook and State of Illinois, have invented certain new and useful Improvements in Safes, of which the following is a specification.

This invention relates to an improvement 10 in safe construction and has particular reference to means for mounting, conveying and housing the door of a safe so that the same may be opened and closed in the usual manner and so that, when opened, it may 15 be moved into a position at right angles with the plane of the face of the safe and housed adjacent to the side wall thereof. It also relates to a system for forming a bank of safes which consists in removing the doors 20 from a position of hinged sealing relation with reference to the door frame of the safe and conveying the same into a position where the door is housed adjacent to the side walls of the safe, and then bringing a 25 plurality of safes, with the doors similarly mounted and disposed, into intimate relation and in alignment, thus accomplishing a material saving in floor space and a peculiar advantage due to the convenience afforded in 30 the utilization of the safe for the purposes for which it is intended.

It has been found that where safes are employed in vaults or offices where there is a limited floor space available, and particularly 35 where a bank of said safes is formed by placing a series of safes side by side, a material part of the floor space is necessarily occupied by the swinging of the doors to an open position. If, for instance, in the 40 use of one safe having two doors, the doors are opened so that the face of the doors and the face of the safe are in a common plane, the doors usually extend beyond the width of the safe and to that extent occupy considerably 45 more space than is occupied by the safe alone. Where, on the other hand, a plurality of safes are placed in one line it is necessary to provide sufficient space between the safes so as to allow for the doors 50 to fully open, thus making it necessary to have a wide space between the safes. If under another form of arrangement the safes are banked wall to wall then the doors when opened will stand in a position perpendicular 55 to the face of the safe, thus occupying

considerable floor space. All such arrangements have serious objectionable features. It is the purpose of this invention to overcome such difficulties and to provide means by which the door or doors of safes may be 60 so mounted that they can be brought into hinged relation with the door frame or swung out of such relation into a position where the door can be conveyed in a plane parallel to the side of the safe and perpendicular to the face thereof, and housed adjacent the side of the safe so that the outer edge of the door, when so housed, will be within the plane of the face of the safe—thus entirely eliminating the objectionable 65 features above referred to for the reason that the door is housed adjacent the side walls of the safe in a space which is substantially the same as the width or thickness of the door. Thus a bank of safes may be 70 assembled in line and under the construction indicated they will be separated only by the width of the safe doors when housed as stated, so that it will be understood that under the conditions described, when the 75 safe is opened the doors are arranged to be swung out of sealing relation with the door frame and run into a housing where they disappear from sight and are effectually disposed of until again required for closure 80 of the safe, whereupon they can be withdrawn from the housing and swung into a position to register with the frame of the safe door.

The construction illustrated and described 85 is capable of use with all forms of safe doors where the relation between the door and its frame is stepped in such way as to permit the free removal of the door from its frame. The construction also contemplates the use 90 of a door frame and a door having interlocking tongue and groove and flange relations which can be brought into registration only when the door is swung in a predetermined 95 arc of a circle.

In this case means is provided in the first instance for the opening of the door within the limitations of said arc of a circle, and when thus moved and the interlocking tongue and groove flanges are released, then 100 the door is swung on a second pivot into a position where it can be moved as stated in a plane perpendicular to the face of the safe, and parallel with the walls thereof.

This invention is illustrated in the accom- 110

panying drawings in which the parts are designated by numerals, like numerals referring to like parts.

Figure 1 is a perspective view partly in section, showing one of the doors of the safe closed and the other partly open.

Figure 2 is a perspective view showing the door removed from its sealing relation with the door frame and moved into a position perpendicular to the face of the safe and parallel to the side wall thereof.

Figure 3 is a perspective view showing the safe door housed adjacent one side of the safe and within a plane represented by the face of the safe.

Figure 4 is a horizontal section taken through the door and side wall of the safe and through the housing mechanism hereafter to be described.

Figure 5 is a spring lock in perspective.

Figure 6 is a diagrammatic view showing the position of safes as commonly assembled, and also the position as assembled under the system employed in the operation of this invention.

Figure 7 is a perspective view of one form of the door supporting and conveying mechanism.

Figure 8 is a detail of an anti-friction device in perspective.

Figure 9 is a perspective view of a second form of door supporting and conveying means, having particular reference to a stabilizer construction.

Figure 10 is a perspective detail view showing anti-friction mechanism, together with cooperative stabilizing mechanism.

Figure 11 is an elevation illustrating anti-friction and stabilizing mechanism employed in said door supporting and conveying means.

1 is the rectangular body of a conventional safe having two doors designated as 2 and 3. To provide for the construction embodying this invention I prefer to extend the top and base and back wall of the safe as indicated as 4, 5 and 6, this extension furnishing a space for the housing of a safe door as hereinafter more fully specified.

For the purpose of carrying out my invention, I have constructed what I characterize as a door supporting and conveying means. Various devices may be constructed for the accomplishment of the purpose contemplated by this means. I have illustrated, as in Figure 7, one of such embodiments wherein a mullion as 7 is provided at either end with a bracket as 8, in which are suitably mounted roller bearings as 9 and 10. The roller 9 is adapted to carry the vertical thrust of the mullion while the idle rollers 10 engage the walls of guiding ways 11 and 12. I characterize the whole construction as anti-friction means adapted to

facilitate the movement of the mullion 7 in suitable ways. 11 and 12 are sheets of metal vertically mounted on the base 5 and on the top extension 4 to form ways within which the mullion 7 and its friction bearing attachments may move in a plane perpendicular to the face of the safe and parallel to the side wall thereof. 13 is a vertical bar suitably secured between the extensions 4 and 5. 14 and 14^a are bars pivotally connected with the mullion 7 at a point not visible in the drawings, while 14^a and 14^b are bars pivotally connected with the upright 13 at 15. 16 is a bar to which are pivotally connected at the end thereof the bars 14 and 14^a, such pivotal point being designated as 15^a. 17 are bearing rollers suitably mounted between the vertical plates 12 and 12^a. The function of these rollers is to bear the weight of the safe door and facilitate its free movement in a plane parallel with the side of the safe. 17^a and 17^b are friction rollers mounted on the side wall of the safe to guide the door in its movement and to prevent injury thereto in the course of such movement. 18 and 18^a are idle rollers adapted to engage the link 25 hereinafter referred to in order to prevent the movement of said link towards the housing until it has been brought into parallel relation with the side wall of the safe. 19 is a spring lock shown in detail in Figure 5, wherein 20 is a pivoted lever having a hook at one end as 21, with a limiting detent as 23. 24 is a post between which and the rear end of the lever is attached a helical spring 22 operating normally to hold the lever against the detent 23.

Referring to Figures 1, 2 and 4, 25 is a link interposed between the mullion 7 and the door 2 and connected with each respectively by hinged connection—to the door by a hinged connection as 26 and to the mullion 7 by a hinged connection as 27.

It will be noted that in Figure 4 I have provided in the frame of the safe tongue and groove formations as 34, and in the door corresponding tongue and groove formations as at 35. These formations are particularly important in the matter of sealing the relation between the door and its frame. It will be noted further that these tongue and groove formations indicated as 34 and 35 can be interlocked only when the door is moved in that predetermined arc of a circle in this instance the center of which is the hinge 26.

In Figures 9, 10 and 11 is illustrated another form of construction of a safe supporting and conveying mechanism, differing however from that previously described and illustrated in Figure 7 in that instead of using the stabilizer bars 14 and 14^a and 16, pivoted as illustrated to maintain the mullion 7 in a vertical position, another struc-

ture is devised to accomplish the same object, but in a different way. In this device a rack 28 is provided which is adapted to cooperate with cog wheels 30 and 31 carried by the rod 29; and in this case the mullion 7 is provided with brackets 32, 32, carrying also the anti-friction bearing wheels 33.

Referring to Figure 6 there will be found 10 a diagrammatic expression illustrating a plan view of the manner in which the safes constructed according to this invention can be formed into a bank for the purpose of economizing floor space as opposed to the 15 present method or system of assembling such bank of safes. In the first of these diagrams, 36 represents the entire bank as assembled and associated, while 39, 39 shows the housing of the safe doors in the space 20 lying between the safes. In the second of these diagrams 37 illustrates the safe and 40 the safe doors. In dotted lines is shown the arc in which the doors must necessarily move and the intermediate space between 25 the safes is also illustrated. In the third of these, 38 indicates the safe while 41 and 41 indicate the doors, the arc of movement being illustrated. Assuming the safes to be uniform in size, in the first diagram indicated as 36, by actual measurement the floor 30 space occupied is 44 square feet; whereas in the second, indicated as 37, the floor space occupied is 67 square feet; whereas in the third, indicated as 38, 66 square feet 35 are occupied. These figures are sufficient to demonstrate the saving of floor space above referred to.

Referring to Figures 1 and 4, it will be noted that the door 2 is hinged to the link 40 25 by the hinges 26, and the link 25 is hinged to the mullion 7 by the hinges 27. The movement of the door on said hinges is illustrated in Figure 4, where it will be noted that the door is mounted to swing in a 45 predetermined arc on the hinge 26, which movement permits the tongue and groove construction 34 in the frame and 35 in the door to interlock as the door is closed, and to move out of such locking engagement 50 when the door is rotated on such hinge 26. The link 25 is held in engagement with the face of the safe by the hook 21 operating through a hole in said link. This hook may be released by a manual movement thereof 55 so as to permit the link 25 to be turned on the hinge 27. In Figure 4 in dotted lines is indicated two positions which the door 2 and the link 25 will assume when they are released from the detent hook 21 and moved 60 as indicated in Figure 4. The rollers 18 and 18 are adapted to engage the link 25 to prevent the movement of that link in the direction of the plane of the movement of the safe supporting and conveying means 65 until said link has been brought into the

plane of the movement of the said conveyor, as indicated in dotted lines in Figure 4 and designated as α . At this point the rear end of the link engages the side wall of the mullion 7 and prevents its further movement 70 in its arc of rotation. When in the latter position the link and door are both in a common plane parallel with the side walls of the safe and perpendicular to the face of the safe. In this position pressure exerted upon the outer edge of the safe door will cause the supporting and conveying means embodying the mullion 7 to move on its ways in a plane parallel to the side wall 75 of the safe and in the course of such movement the safe door will be engaged by the rollers 17 which are adapted partially to support the weight thereof, and in the event that the door should be at all tilted the rollers 17^a and 17^a are provided as anti-friction rollers to support the door and protect its surface from injury as it is moved 80 into its housing.

It is of course important that the mullion 7 should be maintained in a vertical position during the operation of moving the same in its ways. This may be accomplished in various manners; two forms have been illustrated, one in Figure 7 and the other in Figure 9. In Figure 7 what are characterized as stabilizer arms are interposed between the mullion 7 and the vertical upright 13. These arms are hinged to the mullion and upright and also to a vertical arm and they are so constructed, as shown in Figure 1, that pressure exerted upon the mullion will cause the joints to be broken in one direction, and this breaking will be uniform, as shown in Figure 7, until the arms are entirely collapsed as shown in Figure 3. In Figure 8 is illustrated the antifriction devices which are provided for each end of the mullion 7 in order to facilitate the movement of the said mullion in the ways in which it is mounted to move. In Figure 3 is illustrated the door as conveyed by the means above described into its housing.

It will be noted that when housed as stated, the door is confined within a space 115 substantially equivalent to its width at one side of the safe, leaving free access to the safe through the door opening. When it is desired again to bring the door into sealing relation with the door frame of the safe, it is manually withdrawn from its housing until it is brought into a position where on the rotation of the link 25 that link will be 120 parallel with the face of the safe. The door 2 is then moved on its pivotal connection 26 and caused to interlock with the tongue and groove formations of the frame, thus accomplishing a closure of the door.

Referring to Figure 9, which is a modified construction of the door supporting and 125

conveying means, it will be noted that all of the elements which enter into that construction are substantially similar to those shown in Figure 7, with the exception that 5 instead of the stabilizer arms a rack 28 is provided, adapted to engage with the pinions 30 and 31 mounted on the shaft 29. It will be understood that in this construction any pressure exerted upon the mullion 10 7 to move the same backwards and forwards in its ways must necessarily operate to affect the gears 30 and 31 running in the rack 28 so as to maintain the said mullion 7 in a vertical position.

15 It will be understood of course that the door housing device here described may be employed with a safe having either one door or two, and it will be manifest from the statement made with reference to Figure 6 that considerable economy in floor space is accomplished by the use of this device as opposed to the other constructions illustrated in that figure. Another feature of the construction is that it presents a 25 more desirable, unique and satisfactory appearance to absolutely dispose of the doors during the period when the safes are open, leaving free access to the safes without the impediment incident to the position of the 30 doors in those forms of bank assemblage other than that of this invention shown in the diagram Figure 6.

As heretofore stated, I have provided a spring lock such as that illustrated in Figure 5, which cooperates with a link 25 through the medium of a hole in said link so that when the link is brought into parallel relation with the face of the safe it is retained in such relation by reason of said 35 lock, and under such conditions the door of the safe may be opened and closed in the normal manner. This is an important feature for it is sometimes desirable to have access to the safe without operating the 40 entire mechanism as above described to house the door at the side of the safe. By a manual movement of the latch 21 on the other hand the latch may be released so that the door and link may be brought into the 45 plane of movement of the carrier. So in like manner when the door is withdrawn from its housing and swung on its pivot the latch 21 engages the link and holds the same in such relation that the hinge by 50 which the door is attached to the link is the center of the arc of rotation of the door so as to accomplish the interlocking of the flanges on the door and the frame as heretofore described.

55 60 What I claim is:

1. In combination with a safe, a door supporting and conveying means comprising ways in a plane parallel to the side of the safe and perpendicular to the face thereof, a column provided at either end with

anti-friction carriers adapted to move in said ways, a vertical support at one end of said ways and stabilizer bars interposed between said vertical support and said column so as to maintain the column in parallel relation with said vertical support, at the same time permitting its movement toward or away from the said vertical support, means for pivotally connecting said column with said door so that said door may swing into a plane parallel with said ways and be conveyed in said plane to a position parallel to the side of the safe or be withdrawn outwardly to a position where it will swing 70 into closed relation with said safe. 75

2. In combination with a safe, means for supporting and conveying a door for said safe, comprising ways parallel with a side wall of the safe and with each other, and adapted to receive and carry a mullion, a mullion provided at each end with anti-friction mechanism to facilitate the movement of said mullion within said ways, said mullion mounted between said ways, means to maintain said mullion in a vertical position as it moves in said ways, such means comprising stabilizer bars pivoted to the mullion and to suitable supports and broken and hinged centrally to a vertical bar, the safe door being hinged to said mullion, permitting of its movement into the plane of movement of the mullion or into register as 90 a seal for the safe. 95

3. In a safe having a door frame, the latter being formed with a tongue and groove sealing construction and a door provided with corresponding tongue and groove constructions, said tongue and groove constructions being formed to interlock when the door is moved in a predetermined arc of a circle, in combination with door supporting and conveying means operating in a plane parallel with the side walls of the safe and perpendicular to the face of the safe, a link interposed between said door supporting and conveying means and said door, said link being pivotally connected with said supporting and conveying means at one extremity and at the other extremity pivotally connected with the door, said pivotal connection with the door being such that when the link is in a plane parallel to the face of the safe, the door will move in said predetermined arc so as to accomplish the interlocking of the said tongue and groove elements of the door and frame, said pivotal connection between the door supporting and conveying means, the link and the door being such, that the door and the connecting link between the door and the door supporting and conveying means may be brought into the plane of movement of said supporting and conveying means so that when the door and the link and conveying means are in one plane they may be moved 100 105 110 115 120 125 130

in that plane until the outer edge of the door has passed a plane corresponding with the front of the safe.

4. In a safe having a door frame, the latter being formed with a tongue and groove sealing construction, and a door provided with corresponding tongue and groove construction, said tongue and groove construction being formed to interlock when the door is moved in a predetermined arc of a circle, in combination with door supporting and conveying means operating in a plane parallel with the side walls of the safe and perpendicular to the face of the safe, said door supporting and conveying means comprising parallel ways, and a column provided at either end thereof with anti-friction bearings adapted to move in said ways, means for sustaining said column in a vertical position while it is moved in said ways, a link interposed between said column and said door, said link being pivotally connected with said column at one extremity and at the other extremity pivotally connected with the door, said pivotal connection with the door being such that when the link is in a plane parallel to the face of the safe, the door will move in said predetermined arc so as to accomplish the interlocking of the said tongue and groove elements of the door and frame, with means to lock said link in a position so that the pivotal connection of the door therewith will occupy a position central of the arc of rotation which the door is required to make in order to accomplish the interlocking of the flanges of the door and the frame, and means to release said lock, said pivotal connection between the door supporting and conveying means, the link and the door being such that the door and the connecting link between the door and the door supporting and conveying means may be brought into the plane of movement of said column, so that when the door and the link and column are in one plane they may be moved in that plane until the outer edge of the door has passed a plane corresponding with the front of the safe.

5. In a safe having a door frame, the latter formed with a tongue and groove sealing construction, and a door provided with corresponding tongue and groove construc-

tion, said tongue and groove construction being formed to interlock when the door is moved in a predetermined arc of a circle, in combination with door supporting and conveying means operating in a plane parallel with the side walls of the safe and perpendicular to the face of the safe, a link interposed between said door supporting and conveying means and said door, said link being pivotally connected with said supporting and conveying means at one extremity, and at the other extremity pivotally connected with the door, said pivotal connection with the door being such that when the link is in a plane parallel to the face of the safe, the door will move in said predetermined arc so as to accomplish the interlocking of said tongue and groove elements of the door and frame, with means to lock said link in a position so that the pivotal connection of the door therewith will occupy a position central of the arc of rotation which the door is required to make in order to accomplish the interlocking of the flanges of the door and the frame, and means to release said lock, said pivotal connection between the door supporting and conveying means, the link and the door being such that the door and the connecting link between the door and the door supporting and conveying means may be brought into the plane of movement of said supporting and conveying means so that when the door and link and conveying means are in one plane they may be moved in that plane until the outer edge of the door passes a plane corresponding with the front of the safe.

Signed by me at Marietta, Ohio, this 18th day of July, 1923.

MORTIMER H. MOORE.
